(57) **CLAIM**

The ornamental design for a socket module for an electronic relay, as shown and described.

DESCRIPTION

FIG. 1 is a right front perspective view of a socket module for an electronic relay showing our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.
